Application October 10, 1956, Serial No. 43,310

Term of patent 14 years

(Cl. D72—1)

FIG. I.

FIG.3.

FIG.2.

Figure 1 is a view in perspective of a bell housing taken from the bottom, front and one side, embodying my new design;

Figure 2 is a view in perspective taken from the top, front and the same side; and

Figure 3 is a top plan view thereof.

The side of the bell housing that is not shown in Figures 1 and 2 is the same in appearance as the side that is shown.

I claim:

The ornamental design for a bell housing, as shown and described.
